UNITED STATES PATENT OFFICE.

EDWIN A. WEBSTER, OF HAVERHILL, MASSACHUSETTS, ASSIGNOR, BY DIRECT AND MESNE ASSIGNMENTS, TO UNITED SHOE MACHINERY COMPANY, OF PATERSON, NEW JERSEY, A CORPORATION OF NEW JERSEY.

HEEL-NAILING MACHINE.

No. 900,244.

Specification of Letters Patent.

Patented Oct. 6, 1908.

Application filed October 3, 1904. Serial No. 226,959.

To all whom it may concern:

Be it known that I, EDWIN A. WEBSTER, of Haverhill, county of Essex, State of Massachusetts, have invented an Improvement in 5 Heel-Nailing Machines, of which the following description, in connection with the accompanying drawings, is a specification, like characters on the drawings representing like parts.

10 This invention relates to heel nailing machines.

The invention is shown as applied to a heel nailing machine in which is employed a vertically movable cross head having a 15 turret thereon, the arrangement being such that the nails are driven downwardly into the heel while the shoe is held bottom side up. It will be understood, however, that the invention is capable of embodiment in 20 other forms of heel nailing machines—for example, machines in which the nails are driven upwardly or machines in which no turret is used.

In the operation of a heel nailing machine 25 one of the chief difficulties which have been encountered is to prevent the nails from being driven into the heel in such a direction that they will not pass through, or so close to the sides of the heel that they will be en- 30 gaged by the trimming cutter, or the breasting knives, during the operation of finishing the heel. Such occurrences are the cause of

much delay and expense, and while various attempts have been made to provide a means 35 for guiding the nails effectively while they are being driven, yet, so far as I am aware, no mechanism has been produced prior to my invention which will guide and direct the nails so that they may be driven in any 40 desired direction practically without fail. The difficulty of controlling the nails or preventing them from passing too close to the surface of the heel is more often encountered in securing high or fancy leather heels, en- 45 tirely through which a nail of somewhat greater length than the height of the heel must be driven. To avoid this difficulty the nails must be driven with much greater accuracy, and a long nail is, moreover, more 50 likely to be deflected from the desired course, and to be crippled during the operation of

driving than a short nail. Furthermore, many high heels, known as "French heels," are under-cut at the breast, that is, they extend forwardly beneath the shank of the 55 shoe, so that in order to drive the nails so that they will be in the required position in the top lift and yet will pass through the heel without emerging in the breast or without being located so closely thereto that they 60 will be struck by the breasting knife, it is essential that the nails be driven in a direction which is more or less oblique to the face of the heel, and which is approximately parallel to the lower portion of the breast there- 65 of when finished. Furthermore, it is often desirable to drive nails in different directions with the same machine, according to the character of the work operated upon. For instance, the inclination at which a 70 short nail may be driven is much less than that at which a longer nail may be driven, and in securing high heels to shoes it is usually necessary, in order to make a tight joint between the edge of the heel and the 75 heel seat, to attach the heels in sections, each section which is attached being secured by nails which pass entirely through the heel and heel seat and are clenched against the jack, so that nails driven after the first sec- 80 tion has been secured must be accurately guided to avoid striking the nails previously driven.

The object of my invention is the production of a machine in which difficulties of the 85 nature above mentioned may be avoided and in which requirements such as those referred to are completely met.

An important feature of the invention consists in the provision of mechanism for driving a nail or nails into a heel coöperating with means under the control of the operator for varying the path of the nail or nails. The arrangement is such that the nails may be inserted in the heel at different degrees 95 of inclination. There is also provision whereby the nails may not only be driven in a direction oblique to the face of the heel, but, if desired, in a direction perpendicular to the face of the heel. The paths of the nails may 100 be varied to cause them to be inserted in positions inclined either toward the breast or

toward the rear of the heel. According to a convenient construction the paths of the nails are varied by varying their position in nail passages provided with drivers working 5 therein.

Other features of the invention will be hereinafter described and defined in the claims.

In the drawings:—Figure 1 shows, in side 10 elevation, the main operating parts of a heel nailing machine to which my invention may be applied. Fig. 2 is an enlarged sectional view of a nail carrying plate illustrating a simplified form of my invention. Fig. 3 is 15 a similar view illustrating a preferred form of my invention. Figs. 4 and 5 are detail views illustrating different positions of adjustment thereof. Fig. 6 is a detail plan view of the nail deflecting plates. Fig. 7 is 20 a cross section on the line $a-a$ of Fig. 3. Fig. 8 is a view similar to Fig. 3, showing the parts in a different position.

In Fig. 1 is illustrated the main operating parts of a form of heel nailing machine 25 of the well-known type which employs a vertically movable cross head 1 in which a turret 2 is mounted, said turret being supported above a jack 3 which is adapted to hold the shoe bottom side up, the frame of the machine supporting a vertically movable head 4 in which a nail holding plate 7 is provided. Said holder 7 is provided with the usual series of nail holes or chambers 8 which register with the gang of drivers 9 35 mounted on the turret.

The particular invention hereafter described is shown as used in connection with a form of heel nailing machine which is provided with means for supporting a heel between a cross bar 22 and a latch 25 against a pressure plate shown as a face plate 13, said plate being secured to the lower side of the holder, and having a series of nail holes 130, therethrough, which register with the 40 holes 8 of the holder. The nail holes 8 are but slightly larger in diameter than the head of the heel nails which are preferably employed in this connection, said nails being of wire and having a sharp, flat-sided point, 45 and an annular head a short distance from the head end thereof.

A pair of flat, rectangular shaped nail deflecting and guiding plates 11 and 12, preferably of hardened steel, are slidably mounted, one above the other, in a correspondingly shaped recess formed in the under side of the holder 7, said recess being open at its front end. The face plate 13 is also secured in a recess formed in the under side of the 50 holder, the lower surface of said plate being flush with the face thereof and said face plate serving as a support for the plates 11 and 12, which are adapted to reciprocate 55 freely longitudinally of the holder, their

front ends extending a short distance beyond 65 the front end thereof.

A spring 14 is secured at its upper end to the front side of the holder by an adjusting screw 15, the lower end of said spring engaging the protruding front ends of said plates 11 and 12, and the tension of said spring against said plates being adapted to be varied by varying the position of the screw 15. A spring 16 is arranged in a chamber in the holder in line with the lower plate 12, and engages the rear end thereof, so that said plate 12 is spring-pressed in opposite directions, the position in which it is in equilibrium depending upon the relative tension of said springs 14 and 16. Each plate 11 and 12 is provided with a series of nail holes 110, 120, corresponding in size and relative location to the chambers 8 of the holder, the upper ends of said holes 110 and 120 and also preferably the holes 130 in the face plate 13 being counter-sunk or beveled as illustrated in Figs. 3 to 7, so that the diameter of the upper ends of said holes is considerably greater than that of their lower ends.

When both nail guiding plates 11 and 12 are in such a position that the front ends thereof are flush and both bear against the spring 14, their respective nail holes will be almost wholly out of register, the holes in the lower plate 12 being somewhat in advance of the holes in the plate 11, and in such a position that the front portion of the holes of the upper plate are in front of the rear portion of the holes in the lower plate, leaving an open passage which is approximately elliptical, as shown in Fig. 6, and corresponding closely to the cross sectional shape of the pointed ends of the heel nails. The holes in the lower plate 12 are counter-sunk to such an extent that the upper ends thereof will register with the lower ends of the holes in the upper plate under all ordinary conditions, and the length of the upper plate is such, and the extent to which the upper ends of its holes are counter-sunk is such that said plate cannot be pushed inwardly to a position in which the upper ends of its holes will be moved out of register with the lower ends of the chambers 8 in the holder.

Assuming that a nail has been placed in each chamber 8, said nail will fall down so that their pointed ends will pass through both plates 11 and 12 and be held thereby, with their pointed ends a short distance above the lower surface of face-plate 13, with their front sides bearing against the front side of the holes in the upper plate, and their rear sides bearing against the rear sides of the holes of the lower plates, see Fig. 3, the shape of the apertures which are left open being such that the nails will all be turned with their flat sides facing toward the

breast and back of the heel, respectively. When the nails are dropped into chambers 8, an inclined deflecting surface will always be presented to the points thereof, until they pass into the holes 130 of the face plate. If the tension of the spring 14 is decreased by unscrewing the screw 15, the spring 16 will overbalance the same correspondingly, and will force forward the lower plate 12 until the condition of equilibrium is restored. As the lower plate moves forward it will swing the points of the nails forward correspondingly, and, by pressing the sides thereof against the front sides of the holes in the upper plate, the latter will also be moved forward correspondingly. If the tension of spring 14 is increased, the opposite movement will take place, so that by varying the tension of said spring the points of the nails may be swung from a position in which their rear sides bear against the rear sides of the holes 130 in the face plate 13, to a position in which their front sides bear against the front sides of said holes, as illustrated in Figs. 3, 4 and 5, Fig. 3 illustrating the position in which the nails point toward the heel end of the shoe, Fig. 4 a position in which they are held perpendicularly to the upper side of the heel, and Fig. 5 a position in which they point towards the breast of the heel. Obviously, they may be held at any intermediate position by simply adjusting the spring 14.

When the driver gang is forced down through the chambers 8, of the holder, the ends of the drivers will engage the heads of the nails, and force the points thereof down through the plates 11, 12 and 13, and, without varying the inclination at which said nails are held from the inclination thereof at the beginning of this movement, the upper plate will be forced forward against spring 14 and the under plate will be forced rearwardly against spring 16, by the nails, so that the holes of said plates will be brought into a position in which they will be nearly in register with each other, and with the chambers 8, by the time the pointed portions of the nails have been passed through the face plate 13; then, as the ribs at the heads of the nails, which are immediately followed by the drivers, are forced through said holes, said plates will be moved so that said holes will be practically in register. It follows, therefore, that the nails will not only be held by plates 11 and 12 at the desired inclination with relation to the face of the heel at the beginning of the driving movement, or while they are being started into the heel, but that they will also be supported transversely and guided by said plates during the whole of the driving operation. The nails having once been driven into the heel a short distance in the desired direction, they

will not ordinarily be deflected from this direction while passing entirely through the heel, although when the nails are particularly long they should be supported transversely between the drivers and the heel while they are being driven, otherwise there is great liability that they will be bent or crippled before their points are clenched. When the nails are driven from the position of Fig. 3, the rear sides thereof will be supported by the face plate 13 and their front sides will be supported by the spring 14 acting through the upper plate 11; in the position of Fig. 4 they will be supported by the springs 14 and 16, respectively, acting through plates 11 and 12, and in the position of Fig. 5 they will be supported by plate 13 at their front sides and by spring 16, acting through plate 12, at their rear sides. If the nails are not sufficiently supported transversely, it is simply necessary to increase the tension of the springs.

The exact direction in which the nails are driven is of especial importance in securing high heels, for instance, heels which are 1½ or 2 inches thick, as a slight variation of the nails from the desired course is likely to cause them to emerge through the sides of the heels or be driven too close thereto.

While I prefer to employ both plates 11 and 12, for the reason that the nails may be held at any inclination from the extreme forward to the extreme backward inclination, as indicated in Figs. 5 and 3, respectively, yet if such extreme inclinations only are desired, the lower plate may be omitted and a single plate, as 20, may be provided between the face plate 13 and the carrier, as illustrated in Fig. 2, said plate being provided with suitable counter-balancing springs 14' and 16'. It will be obvious that if the nails were driven upwardly into the work, instead of downwardly, the function of the deflecting plates would be the same.

The above described deflecting means is durable and unlikely to get out of order, but it is principally advantageous in that it controls all the nails uniformly, and enables the operator, by adjusting a single screw, to vary uniformly the manner in which they shall all be controlled.

Having thus described my invention, what I claim as new and desire to secure by Letters Patent is:

1. In a nailing machine, a nail holder having a series of nail chambers therein leading to its face, a nail deflecting plate movable over the face of said holder and having a corresponding series of nail holes therethrough, means for holding said plate with its nail holes partly out of register with said chambers, and permitting movement thereof to bring said holes into register therewith,

and a gang of drivers movable in said chambers, substantially as described.

2. In a nailing machine, a nail holder having a series of nail chambers therein leading to its face, a nail deflecting plate movable over the face of said holder and having a corresponding series of nail holes therethrough, a spring for holding said plate with its nail holes partly out of register with said chambers, and permitting movement thereof against the action of said spring to bring said holes into register therewith, and a gang of drivers movable in said chambers, substantially as described.

3. In a nailing machine, a nail holder having a series of nail chambers therein leading to its face, a work support, a pair of nail deflecting plates between the face of said holder and said support, each having nail holes therethrough corresponding to said chambers, and means for holding said plates with their respective nail holes partly out of register with each other, and permitting them to be moved into register with each other and with said chambers, and a gang of drivers movable through said chambers, substantially as described.

4. In a nailing machine, a nail holder having a series of nail chambers leading to its face, a nail deflecting plate having a series of nail holes therethrough and movable over the face of said holder to bring said holes into coincidence with said chambers, two springs acting to move said plate in opposite directions, and arranged to hold said plate in equilibrium with its nail holes partly in register with the ends of said chambers, means for varying the tension of one of said springs to vary the position of said plate, and a gang of drivers movable in said chambers, substantially as described.

5. In a nailing machine, a nail holder having a series of nail chambers leading therethrough, a face plate secured thereto and having a corresponding series of nail holes therethrough, in register with said chambers, and a nail-deflecting plate also having a corresponding series of nail holes therethrough and slidably mounted between said holder and face plate, and means for holding said deflecting plate with its nail holes partly out of register with the ends of said chambers and permitting movement thereof to bring said holes into register therewith to permit the passage of the nails therethrough, and a driver gang movable in said chambers, substantially as described.

6. In a nailing machine, a nail holder having a series of nail chambers leading therethrough, a face plate secured thereto and having a corresponding series of nail holes therethrough in register with said chambers, a pair of nail deflecting plates

having a corresponding series of nail holes therethrough, and slidable one upon the other, and with relation to said holder, between said holder and said face plate, means for yieldingly holding said deflecting plates with their holes partly out of register and permitting movement thereof into register with each other and with said chambers, and a driver gang movable in said chambers, substantially as described.

7. In a nailing machine, a nail holder having a series of nail chambers leading to the face thereof, a nail-deflecting plate having a corresponding series of nail holes therethrough, and movable over the face of said holder to bring its holes into register with said chambers, said holes being of greater diameter than said chambers at their adjacent ends and tapering to approximately the same diameter, and means for holding said plate with its holes partly out of register with the ends of said chambers, and a gang of drivers movable in said chambers, substantially as described.

8. In a nailing machine, a nail holder having a series of nail chambers therein leading to its face, a pair of nail deflecting plates adjacent the face of said holder, each having nail holes therethrough corresponding to said chambers, a spring for holding said plates with their respective nail holes partly out of register with each other, said plates being movable to bring their holes into register with each other and with the ends of said chambers, and a driver gang in said chambers, substantially as described.

9. In a nailing machine, a nail holder having a series of nail chambers therein leading to its face, a pair of nail deflecting plates adjacent the face of said holder, each having nail holes therethrough corresponding to said chambers, a spring arranged to engage adjacent ends of said plates simultaneously and to hold them with their respective nail holes partly out of register with each other, a spring bearing against the opposite end of one of said plates and acting in opposition to said first named spring, said plates being movable to bring their holes into register with each other and with the ends of said chambers, and a driver gang in said chambers, substantially as described.

10. In a nailing machine, a nail holder having a series of nail chambers therein leading to its face, a pair of nail deflecting plates adjacent the face of said holder, each having nail holes therethrough corresponding to said chambers, a spring arranged to engage adjacent ends of said plates simultaneously and to hold them with their respective nail holes partly out of register with each other, and means for varying the tension of said spring, a spring bearing against

- the opposite end of one of said plates and acting in opposition to said first named spring, said plates being movable to bring their holes into register with each other, and 5 with the ends of said chambers, and a driver gang in said chambers, substantially as described.
11. In a nailing machine, a nail holder having a series of nail chambers passing therethrough and a gang of drivers movable therein, a face plate secured to the under side of said holder and having a series of nail holes therethrough in register with said chambers, a pair of nail deflecting plates 10 arranged between said face plate and holder, and having a corresponding series of nail holes therethrough beveled at their upper ends, a spring arm arranged to engage adjacent ends of said deflecting plates simultaneously and to hold them with their respective nail holes partly out of register with each other, and means for varying the tension of said arm, a spring engaging the opposite end of the lower plate from said 15 spring arm and acting in opposition thereto, said plates being movable to bring their holes into register with each other and with the ends of said chambers, substantially as described.
12. In a nailing machine, a nail holder having a series of nail chambers therein, a driver gang movable in said chambers, and means, movable transversely of said chambers, for simultaneously moving the nails therein to different positions of parallelism, substantially as described.
13. In a nailing machine, a nail holder having a series of nail chambers therein, a driver gang movable in said chambers, and 20 means, movable transversely of said chambers, for holding the nails therein approximately parallel to each other and for simultaneously moving them to different positions of parallelism, substantially as described.
14. In a nailing machine, a nail holder having a series of nail chambers therein, a driver gang movable in said chambers, and means for holding the nails therein in predetermined relative positions and for simultaneously moving them transversely to different corresponding positions, substantially as described.
15. In a nailing machine, a nail-holder 25 having a nail chamber therein, a driver and a nail guide adjustable transversely of said chamber for holding the nail at different inclinations therein, substantially as described.
16. A heel attaching machine, having in combination, a shoe support and a pressure plate arranged for relative movement to press a heel on the heel seat of a shoe, mechanism for driving a group of nails into the 30 heel and the heel seat and adjustable means for varying the path of the nails with relation to the face of the pressure plate.
17. A machine of the class described, having in combination, a work support and a pressure plate arranged for relative movement to subject a heel to pressure, mechanism for driving a group of nails into the heel and means for controlling the path of the nails constructed for adjustment to vary the degree of inclination to the face of the 35 pressure plate at which the nails are driven.
18. A machine of the class described, having in combination, a work support and a pressure plate arranged for relative movement to subject a heel to pressure, mechanism for driving a group of nails into the heel while held under pressure and means for controlling the path of the nails constructed for adjustment to cause the nails to be driven in a predetermined direction either 40 perpendicular to or oblique to the face of the pressure plate.
19. A machine of the class described, having in combination, a work support and a pressure plate arranged for relative movement to subject a heel to pressure, mechanism for driving a group of nails into the heel while held under pressure and means for controlling the path of the nails constructed for adjustment to cause them to be inserted 45 in predetermined positions inclined either toward the breast or toward the rear of the heel.
20. In a machine of the class described, the combination with a nail holder having 50 driver passages, and drivers arranged to move in said passages, of means for controlling the position of nails in said passages constructed to permit the nails to be held in the path of the drivers at different degrees 55 of inclination.
21. A heel attaching machine, having, in combination, means for sustaining a shoe and a heel in attaching position, mechanism for driving nails into the heel and heel seat, and mechanism independent of said sustaining 60 means for varying the path of the nails.
22. A heel nailing machine comprising a longitudinally movable driver, for inserting a nail in a heel, and means for guiding the nail at different predetermined inclinations with relation to the path of the driver as the nail is driven thereby.
23. A heel nailing machine comprising a longitudinally movable driver, and an adjustable nail guide for guiding a nail at different inclinations with relation to the path of the driver.
24. A heel nailing machine comprising a nail holder having a nail hole of larger diameter than the nail to be driven, means for

holding the point end of the nail in different positions in said hole and a driver for forcing the nail into a heel while thus held.

25. A machine of the class described, having in combination, a shoe support and a pressure plate arranged for relative movement to press a heel upon the heel seat of a shoe, drivers arranged for movement in said pressure plate in a direction perpendicular to the face of said plate, and means for varying the angle relatively to the face of

the pressure plate at which the nails are forced from the pressure plate into the heel by the drivers.

In testimony whereof, I have signed my name to this specification, in the presence of two subscribing witnesses.

EDWIN A. WEBSTER.

H. B. DAVIS.

It is hereby certified that in Letters Patent No. 900,244, granted October 6, 1908, upon the application of Edwin A. Webster, of Haverhill, Massachusetts, for an improvement in "Heel-Nailing Machines," an error appears in the printed specification requiring correction, as follows: Page 5, lines 65 and 66 should be transposed; and that the said Letters Patent should be read with this correction therein that the same may conform to the record of the case in the Patent Office.

Signed and sealed this 27th day of October, A. D., 1908.

[SEAL.]

C. C. BILLINGS,

Acting Commissioner of Patents.
